UNITED STATES PATENT OFFICE.

DAVID NEWTON GREEN, OF COMMERCIAL POINT, OHIO.

GRAIN-BINDER.

SPECIFICATION forming part of Letters Patent No. 331,493, dated December 1, 1885.

Application filed February 4, 1884. Serial No. 119,784. (No model.)

To all whom it may concern:

Be it known that I, DAVID NEWTON GREEN, of Commercial Point, in the county of Pickaway and State of Ohio, have invented a new 5 and useful Improvement in Grain-Binders, of which the following is a full, clear, and exact description.

Reference is to be had to the accompanying drawings, forming a part of this specification, 10 in which similar letters of reference indicate corresponding parts in all the figures.

Figure 1, Sheet 1, is a side elevation of my improvement, the shaft being shown in section. Fig. 2, Sheet 1, is a sectional elevation of the 15 same. Fig. 3, Sheet 2, is a section of the same, taken through the line $x-x$, Fig. 1. Fig. 4, Sheet 2, is an elevation of the same. Fig. 5, Sheet 2, is a sectional side elevation of the same, taken through the line $y-y$, Fig. 4, parts 20 being broken away and in section. Fig. 6, Sheet 2, is a sectional elevation of a part of the same, illustrating the grasping of the twine, part being broken away. Fig. 7, Sheet 2, is an elevation of a part of the same, illustrating 25 the tying of the knot. Fig. 8, Sheet 2, is a view showing the completed knot and a section of the twine-grasper.

The object of this invention is to provide improved grain-binders designed especially 30 for application to the Appleby grain-binding harvesters, but applicable to other grain-binding harvesters, and which shall be simple in construction and reliable in operation.

The invention consists in the construction 35 and arrangement of parts, as will be herein-after fully described and claimed.

A is the cam and gear wheel, which is attached to the shaft B, driven from the driving mechanism of the harvester in the ordinary 40 manner. The cam and gear wheel A is provided with a laterally-projecting rim, C, having an inwardly-projecting flange, D, upon its outer edge.

To the inner surface of the rim C is attached 45 a section of gear-teeth, E, into which mesh the teeth of the knotter-pinion F, and which are sufficient in number to revolve the knotter-shaft once for each revolution of the cam and gear wheel A. The flange D of the cam and 50 gear wheel A is designed to engage with a shoe, G, attached to or formed upon the knot-

ter-shaft or the pinion F, to hold the said knotter-shaft from turning, and the flange is cut away opposite the gear-teeth E, to allow the said knotter-shaft to revolve when the 55 pinion comes into engagement with the said gear-teeth E. The knotter-pinion F is attached to the shaft of the knotter H, which revolves in bearings in the frame I, through which the shaft B passes, and which frame is 60 designed to be held stationary by an arm (not shown in the drawings) attached to a shoulder or flange, J, of the said frame I. The twine is guided to the knotter H by the curved cord guide and deflector K, the outer or notched 65 end of which rests in a recess in the lower part of the frame I. The inner end of the cord guide and deflecting arm K has a small roller, L, pivoted to it, and rests in a groove, M, in the face of the cam and gear wheel A. 70 In the side walls of the groove M is formed an offset or cam, N, which comes in contact with the roller L, and operates the cord guide and deflector K to bend the twine laterally over the knotter-jaws just before the knotter H begins to revolve. As soon as the knotter H has caught the twine the cord guide and deflector K moves back to its former position. 75

In the face of the cam and gear wheel A is formed a recess or depression, O, to allow the 80 movable cord-clamp P to be drawn back to release the twine.

To the side of the shank of the movable cord-clamp P is pivoted a small roller, Q, to roll along the face of the cam-wheel A. The movable cord-clamp P is drawn back to release the twine by the inclined projection or cam R, attached to or formed upon the outer wall of the groove M, and against which the roller Q of the said movable clamp strikes. As the 85 roller Q passes out of the inclined end of the recess O the movable clamp P is pushed forward to again clamp the twine. The forward part of the movable clamp P is slotted to receive the stationary cord-holder plate or arm S, and has recesses T formed in its upper 90 edge to receive the twine and press it against the edge of the said arm S. The inner part or prong of the movable clamp P passes between the cord-holder plate or arm S and the 95 knife U, the shank of which is secured to the cord-holder plate or arm S, with its edge a 100

little above the lower edge of the said plate or arm S, so that the twine will be clamped before it is cut.

V is the movable jaw of the knotter, which 5 passes through and is pivoted in a slot in the fixed jaw of the knotter H, and is closed at the proper time by a curved cam, W, secured to the upper end of a spring, W', attached at its lower end to the frame I. The movable 10 jaw V is opened to grasp the twine by an inclined projection, X, formed upon or attached to the frame I. When the needle Y brings the twine around the sheaf, as soon as the twine is brought over so far that the cord 15 guide and deflecting arm K, that guides the twine to the knotter H, catches the twine, the said cord guide and deflecting arm begins to move before the needle has completed its forward movement. As the knotter H begins to 20 revolve and has turned part way, the movable jaw V is opened by the projection X, and when the said knotter-hook has turned far enough to catch the twine held by the cord-holder, consisting of the movable clamp and 25 the stationary plate or arm, the movable jaw V closes upon the twine, and the knotter continues its revolution to its former position. When the movable jaw V of the knotter closes upon the twine, the movable clamp 30 P opens and releases the twine previously held by it, and by the time the knotter H has completed its revolution the movable clamp P again clamps the new twine and presses it against the knife U and cuts it off. 35 It will be observed that the cord-holder clamps the twine but once, and the knife cuts it off but once, and that the knot is stripped from the knotter by the discharge of the bundle from the binding-table by the arm B, attached 40 to the cam and gear wheel A.

Having thus described my invention, I claim as new and desire to secure by Letters Patent—

1. In a grain-binder, the combination, with the cam and gear wheel A, having a recess, 45 O, and projection R, of the knotter operated by said wheel, and the cord-holder comprising the fixed plate S, at right angles to the axis of the cam and gear wheel, and the movable clamp P, at right angles to the plate S, and

provided with a notch, T, adjacent to the inner edge of the said plate S, substantially as set forth.

2. The combination, with the shaft B, the cam and gear wheel A thereon, and the frame I, of the knotter operated from the said wheel, 55 the movable cord-clamp P, operated from the cam and gear wheel, the said clamp being forked at its outer end and notched at T on the inner edge of said notched portion, and the stationary plate S, fixed to the frame I and 60 extending through the forked end of the clamp P, substantially as set forth.

3. The combination of the frame I, the cam and gear wheel A, provided with the rim C, inwardly-projecting flange D, and gear-teeth 65 E, of the knotter H, the shaft of which is provided with a pinion, F, and shoe G within the flange D, the movable jaw V, pivoted to the knotter, the cam X, the cam W, and spring W', substantially as set forth.

4. The combination of the cam and gear wheel A, having gear-teeth E, cam-groove M, and cam N on the inner wall of the groove facing the gear-teeth, and the knotter H V, the pinion F on the shaft thereof, and the cord 70 guide and deflector K, pivoted to swing laterally, as shown, one end of the said guide resting in the cam-groove, and the other end having a notch at right angles to said guide, as shown, whereby the cam N will cause the cord 75 guide and deflector to bend the twine laterally over the knotter-jaws just before the knotter-pinion F is operated by the gear teeth E to revolve the knotter, and the said cord-guide be returned to its normal position as soon as the 80 knotter has caught the twine, substantially as 85 set forth.

5. In a grain-binder, the combination, with the cam and gear wheel A, of the forked movable clamp P, the fixed arm or plate S, at right 90 angles thereto and extending through the fork, and the knife U, fixed to the frame adjacent to the inner face of the inner prong of the forked clamp, substantially as set forth.

DAVID NEWTON GREEN.
